UNITED STATES PATENT OFFICE.

JAMES H. RAND, OF NEWTON, MASSACHUSETTS.

INDICATOR DEVICE.

1,149,081.

Specification of Letters Patent. Patented Aug. 3, 1915.

Application filed April 5, 1912. Serial No. 682,709.

To all whom it may concern:

Be it known that I, JAMES H. RAND, a citizen of the United States, and resident of Newton, in the county of Middlesex and State of Massachusetts, have invented new and useful Improvements in Indicator Devices, of which the following is a specification.

This invention relates to adjustable index or indicator devices of the kind in which a supporting frame holds a series of removable and interchangeable protective sheaths of transparent material, in which are incased removable and interchangeable index or indicator cards or slips, and the invention consists particularly in the novel and improved features of the sheaths and indicator slips, in combination, as hereinafter described and pointed out in the claims.

In the accompanying drawings which illustrate certain embodiments of the invention,—Figure 1 is a plan view of one of the transparent sheaths forming part of my invention; Fig. 2 is a cross sectional view of one form of the invention showing the several parts assembled; Fig. 3 is a plan view of one of the main indicator strips; Fig. 4 is a plan view of one of the subsidiary indicator strips; Fig. 5 is a plan view of the assembled parts shown in the foregoing figures; and Fig. 6 is a plan view of a modification of the invention showing the manner of assembling the parts.

In indicator or index devices of the character to which this invention relates, bearing name and address lists, or other data or reference characters, if it is desired to change the inscription in part, either permanently or temporarily, it has heretofore been necessary to discard the indicator card or slip and write a new one, thus increasing the work and the consumption of material. For example, in an address list, if the address of "Doe Listing Co., 32 Canal street, Boston, Mass.", (Fig. 3) is changed to "408 Bridge street, New York," it has been the practice to throw away the existing slip and write a new slip entire in place thereof. As the slips frequently contain not only the names and addresses, but other memoranda or data, this necessity of re-writing the slip when a change occurs not only makes some work and takes time, but also involves the risk of mistake in copying the inscriptions.

With my invention the desired change

can be made by inserting between the sheath and that part of the indicator slip containing the inscription to be changed, a subsidiary slip bearing the new or altered inscription, covering only part of the main slip and leaving exposed those parts which bear the permanent inscription or the inscriptions which are not desired to be changed.

Referring to the drawings, *a* represents a long and relatively narrow sheath, of celluloid, or other suitable transparent, protective material, the edges of which are bent to provide flanges or lips *a'*, forming with the face of the sheath two opposed channels *a''* in which indicator slips may slide. In practice a number of such sheaths are removably and interchangeably mounted in a frame (not shown) having inwardly facing guide channels to engage the ends of the sheaths in the usual manner.

The transparent sheath *a* has a closed front face, as shown, and is open at its ends to permit indicator strips to be inserted and removed by sliding them through the ends of the sheath. An indicator slip or strip *b* is removably held within said sheath, and is of substantially the same length and width as the length and width of the interior of the sheath, thus being substantially coextensive in area with the interior area of the face of the sheath. This indicator strip or slip *b* may be termed the main indicator slip, and is inscribed with such matter as is appropriate to the use to which the index device is to be put. In the form herein illustrated in Figs. 3 and 5, the inscription consists of a name and address, the name occupying the upper half of the slip and the address the lower half.

In order to alter the inscription without discarding, or mutilating, or even removing the main slip from its sheath, I provide a subsidiary slip of smaller area than the main slip, which will slide in and out of the sheath between the main slip and the face of the sheath, to cover a part of the main slip, which bears the part of the inscription to be changed. In the form of the invention shown in Figs. 2, 4 and 5, such subsidiary slip *c* is of the same length as the main slip, but half the width of the main slip. Assuming that the change desired is a change of address from "52 Canal street, Boston, Mass." to "408 Bridge street, New York," without changing any other part of the in-

scription on main slip *b*, the subsidiary slip *c* is inserted into the sheath in position to cover and conceal the longitudinal lower margin of the main slip, thus screening the old address and exhibiting in place thereof the new address, which is inscribed on slip *c*, but leaving the remaining inscriptions on slip *b* exposed. Should the address on slip *c* be a temporary address, the original address may be again restored to view by simply withdrawing the subsidiary slip *c*, which may be stored in the sheath behind main slip *b*, in case it should be required for use again, as frequently happens, as in cases, for example, where lists are required to show alternately a permanent and a summer address. Thus the indicator or index may be quickly and conveniently altered in respect to part of its inscriptions, or restored again to its original condition, without the necessity of copying or rewriting any part of the main slip, which would involve labor, and danger of mistakes, and without even removing the main slip from the sheath.

In the modification shown in Fig. 6, the sheath *a* and the main indicator slip *b* are the same as already described, excepting that the inscription on the slip *a* shows the name on the left hand end of the slip and the address on the right hand end, instead of on the upper and lower parts respectively, as in Fig. 3. In such case, in order to change the inscription at one end of the main slip, as distinguished from the longitudinal margin as before, I provide the subsidiary slip *c'*, which bears the new or altered inscription, and slides into the sheath, covering that portion of the main slip which is to be changed, and leaving other parts of the main slip exposed. The slip *c'* is shown in Fig. 6 as partially withdrawn from the sheath.

It will thus be seen that in either form of the invention the subsidiary indicator strip is of smaller area than the main strip so as to partially cover the face of the main strip leaving part thereof exposed, and that one of the dimensions of the face of the subsidiary strip,—the longitudinal dimension of strip *c* and the transverse dimension of strip *c'*,—is substantially the same as the corresponding interior dimension of the sheath.

In order to facilitate the removal of the slips from the sheath, I have provided in one or both ends of the sheath a notch *a'*. By inserting a pointed implement, or a finger nail

of the user, into this notch the slips may be pushed far enough out of the sheath to enable the projecting end to be seized by the fingers and the slips withdrawn. Or, the slips may be seized within the notch and withdrawn. Said notches may also be used, in the form of the device shown in Fig. 5, to admit a pointed implement to straighten or adjust the subsidiary slip laterally, after it has been inserted in the sheath, in case it should not lie straight, or should wholly or partially cover the wrong part of main slip *b*; and further, by reason of said notches the subsidiary slip may be withdrawn, if desired, by a pointed implement without disturbing the main slip.

I claim:

1. In combination, a transparent sheath having a closed front face adapted to receive and hold removable indicator slips, a main removable indicator slip adapted to slide in and out of said sheath, and being of substantially the same length and width as the length and width of the interior of said sheath, and a subsidiary indicator slip narrower than the main slip, adapted to slide in and out of said sheath between the main slip and said closed front face of the sheath and to cover one longitudinal margin of said main slip leaving the other margin thereof exposed.

2. In combination, a sheath of transparent sheet celluloid having a closed front face and inturned guide flanges, said sheath being open at its ends to permit indicator strips to be inserted and removed through the ends, a main removable indicator strip adapted to slide in and out of said sheath and being of substantially the same length and width as the length and width of the interior of the sheath, and a subsidiary indicator strip of smaller area than the main strip, so as to partially cover the main strip leaving part thereof exposed, one of the dimensions of the face of said subsidiary strip being substantially the same as the corresponding interior dimension of the sheath, and said subsidiary strip being adapted to slide in and out of the sheath through its open end, between the main strip and the closed front face of the sheath.

Signed by me at Boston, Massachusetts, this 23rd day of March 1912.

JAMES H. RAND.
